Int. Cl. D9—01

U.S. Cl. D9—9

FIG. 1 is a perspective view of an aerosol container showing my new design;

FIG. 2 is a front elevational view;

FIG. 3 is a top plan view; and

FIG. 4 is an elevational view looking from the left of FIG. 2.

The characteristic features of my design reside in the configuration and appearance of the combined actuator cap and dispensing tube on a container as shown.

I claim:

The ornamental design for an aerosol container, as shown and described.
